CLAIM

(21) Appl. No.: **29/132,142**

The ornamental design for an antiperspirant and/or deodorant product, as shown and described.

(22) Filed: **Nov. 2, 2000**

DESCRIPTION

(51) **LOC (7) Cl. 28-02**

FIG. 1 is a perspective view of an antiperspirant and/or deodorant product showing the new design;

(52) **U.S. Cl. D28/4**

FIG. 2 is a top plan view of the antiperspirant and/or deodorant product of FIG. 1;

(58) **Field of Search** D28/4, 7, 8.1, D28/76, 77; D9/337, 338, 520, 558, 414, 424; 132/317, 318, 320; 206/385, 581, 823; 401/6, 17, 35, 49-98, 170-182; 424/78.02, 78.03, 63-68, 401; 510/146

FIG. 3 is a front elevation view of the antiperspirant and/or deodorant product of FIG. 1, the rear elevation view being the same;

(56) **References Cited**

FIG. 4 is a side elevation view of the antiperspirant and/or deodorant product of FIG. 1, the other side elevation view being the same;

U.S. PATENT DOCUMENTS

FIG. 5 is a perspective view of a second embodiment of the antiperspirant and/or deodorant product; and,
